UNITED STATES PATENT OFFICE.

RICHARD VARLEY, OF ENGLEWOOD, NEW JERSEY, ASSIGNOR TO THE AUTOCOIL COMPANY,
A CORPORATION OF NEW JERSEY.

IGNITION SYSTEM, FOR EXPLOSION-ENGINES.

No. 915,639.

Specification of Letters Patent. Patented March 16, 1909.

Original application filed December 1, 1906, Serial No. 345,864. Divided and this application filed June 4, 1908.
Serial No. 436,542.

To all whom it may concern:

Be it known that I, RICHARD VARLEY, a citizen of the United States, residing at Englewood, in the county of Bergen and 5 State of New Jersey, have invented certain new and useful Improvements in Ignition Systems for Explosion-Engines, of which the following is a full, clear, and exact description.

10 This invention relates to ignition systems for explosion engines, and more particularly to an arrangement by which the duration of the primary circuit closure is varied with respect to the stroke of the engine.

15 The ordinary circuit controlling device for an ignition system is driven by the engine and closes the circuits of an induction coil, or, more generally, a plurality of induction coils at fixed intervals and for a predetermined duration or "dwell." The longer the period of circuit closure or dwell, the more certain the ignition becomes, but, on the other hand, a long circuit closure consumes an excessive battery current, and, in many 20 cases uselessly, since the engine ordinarily operates properly with very short current duration. Some means for regulation is desirable, especially as the controlling device is driven by the engine so that the primary 25 dwell is less at high speeds than at low speeds.

It is the principal object of my present invention to have the primary circuit closure or dwell controllable so as to be suited to the 30 conditions.

35 In my prior application filed Dec. 1, 1906, Serial No. 345,864, of which the present case is a divisional application, the present construction was set forth as an alternative 40 form of an invention for accomplishing the above stated purposes. The present construction includes, however, several broadly stated features of invention distinct from the subject matter to which said parent case 45 is now restricted.

The invention of the present application may be said to consist in a means for effecting the above described variation of the primary circuit closure or dwell by the use of 50 separate controllers or banks of segments having a common rotatable element and having the segments or contacts of different angular extents in the different series or banks, and which are adapted to be used in

a multiple or parallel circuit at certain times. 55 At other times, only the bank or series of short segments or contacts is used.

The invention more particularly consists in the features of construction and combination as hereinafter set forth and shown and 60 finally particularly pointed out in the appended claims.

In the drawings: Figure 1 is a diagrammatic view showing an ignition system and circuit controller embodying the principles 65 of my invention. Fig. 2 is a vertical sectional view through the circuit controller.

In the form of the invention shown there are two separate arms 13 and 14 each having a roller 15 and 16 and each spring impelled 70 outward by springs 17, 18 indicates segments in the path of the roller 15, and 19 denotes segments in the path of the roller 16. The segments 18 are longer than the segments 19. In practice the segments 18 may 75 be made twice as long as the segments 19, for example, 50° and 25° of angular range respectively. All of these segments are embedded in the usual insulating casing 20, so as to be concentric with the shaft 1. The 80 arm 13 is permanently grounded on the shaft 1, but the arm 14 is insulated from the shaft 1, but has a plate 21 by which continuous electrical connection is made with the brush 22. The battery and induction coils are 85 denominated B and C', C², C³, and C⁴, respectively. The battery has terminals l' and l'', and the coils C' C² C³ C⁴ have connections n', n², n³, n⁴ with the segments 18. Additional connections o', o², o³, o⁴ are, however, provided 90 to connect the segments 18 with the corresponding segments 19. The battery terminal l' has a permanent connection with brush 22 and also with switch arm 23, and a ring 24, concentric with the shaft 1. The switch 95 arm moves into and out of contact with the permanently grounded contact stud 25, and the ring 24 may be grounded by rollers 26 normally spring pressed inward, but adapted to be thrown outward by centrifugal force. 100

A mechanical construction for these rollers is shown in my Patent No. 885,894, and forms no part of the present invention.

The operation is as follows: With the parts in the position shown, current flows 105 from battery B, through wire l', wire m', coil C⁴, vibrator v, wire n⁴, wire o⁴, segment 19, roller 16, arm 14, plate 21, brush 22, and

- wire 7², back to battery. There is no circuit through the segments 18 because the terminal 7² of the battery is not grounded under these circumstances, so that there can be no completion of the battery circuit by the action of the roller 15 in grounding the segments 18. The primary circuit closure or dwell therefore corresponds only to the length of the segments 19, amounting to about 25°, for example, as above stated. This corresponds to normal running conditions, but if it is desired to attain high speed or climb a hill, the switch arm 23 is moved on to point 25, so as to establish a ground connection for the battery terminal 7². Under these circumstances the grounding of segments 18 becomes effective to complete the primary circuits in an obvious manner, and the circuit closure or dwell is for the entire length thereof corresponding to about 25° or 50° in practice. This result may be secured automatically by having the rollers 26 fly outward at a definite speed to engage the ring 24. When this occurs the primary circuits of the induction coils are completed during the entire length of time that the roller 15 is in contact with the long segments 18, instead of the shorter interval while the roller 16 is in contact with segments 19. The primary dwell is therefore lengthened with respect to the engine stroke when the rollers 26 fly outward. The adjustment may be set for 30 miles an hour, so that the ring 24 is automatically grounded at this speed and the increased dwell provided for.
- The rollers or other contact arms 15 and 16 are, of course, adapted to initially engage their respective segments at the same moment, so that the beginning of the circuit closure occurs at the same time whether only one or both are in the circuit. In case both are in the circuit, however, the circuit closure or dwell continues for a longer period in the engine stroke, although this may not be an actually longer time interval, as the engine is generally running rapidly when the long segments are used. The operator therefore experiences no noticeable change of conditions in going from one circuit condition to the other. This is very important as it would, of course, be impracticable to have to change the position of the circuit controller whenever the circuit conditions were changed by the switch 23.
- I do not, of course, desire to be limited or restricted to the particular construction of circuit controller having segments and a revolute arm as shown, nor to the particular number of coils shown.
- What I claim is:
1. In an ignition system having a primary circuit, a pair of members adapted to have a continuous angular displacement with respect to one another in one direction, contacts carried by one of said members, and contact

arms carried by the other of said members, the different contact arms respectively having an engagement of different angular extent with the contacts engaged thereby, and means for completing a primary circuit of said ignition system through one of said arms, or more than one of said arms in a multiple circuit, whereby the primary dwell is varied.

2. In an ignition system, an induction coil and a primary circuit controller therefor, including a plurality of rotating contact arms, contacts of different angular extent in the paths of said contact arms, and means for including the contacts of one angular extent, or the contacts of another angular extent simultaneously in parallel with said contacts of one angular extent, in said primary circuit, whereby the primary dwell is varied.

3. In an ignition system, an induction coil and a primary circuit controller therefor, including a plurality of rotating devices in different planes, sets of contacts in the planes of different of said devices, the contacts of different sets having a different angular extent, and means for including the contacts of different sets and their corresponding devices in said primary circuit, whereby the primary dwell is varied.

4. In an ignition system, an induction coil and a primary circuit controller therefor, including a plurality of rotating devices in different planes, and contacts in the planes of different of said devices, the contacts of different planes having a different angular extent, contact studs corresponding in number to all of said respective planes, and a switch element forming a terminal of the primary circuit and adapted to engage said contact studs selectively, whereby the contacts of a greater or less number of said planes are included in the primary circuit, and the primary dwell varied.

5. In an ignition system having a primary circuit, a circuit controller having a plurality of contacts of different angular extents and located in different transverse planes, and a switch for putting the contacts of one or more than one of said planes simultaneously in said circuit.

6. In an ignition system having a primary circuit, a circuit controller having a plurality of contacts of different angular extents and located in different transverse planes, a continuously rotating shaft having metallic parts in different planes to engage said contacts, and a switch for putting the contacts of one or more than one of said planes simultaneously in said circuit.

7. In an ignition system, an induction coil and a primary circuit controller therefor, including a plurality of rotating devices in different planes and contacts in the planes of different of said devices, the contacts of different devices having a different angular extent,

and automatic means controlled by the speed of the engine for including the contacts of different planes and their corresponding devices in said primary circuit, whereby the primary dwell is varied.

8. In an ignition system, an induction coil and a primary circuit controller therefor, including a plurality of rotating devices in different planes and contacts in the planes of different of said devices, the contacts of the different devices having a different angular

extent, and a centrifugally operated device for automatically including the contacts of different planes and their corresponding devices in said primary circuit, whereby the primary dwell is varied.

In witness whereof, I subscribe my signature, in the presence of two witnesses.

RICHARD VARLEY.
